CLAIM

The ornamental design for a conveyor belt, as shown and described.

DESCRIPTION

FIG. 1 is an isometric view of the top, front, and right side of the conveyor belt, in condition of use;

FIG. 2 is an enlarged view thereof;

FIG. 3 is a front elevational view of the conveyor belt of FIG. 2;

FIG. 4 is a rear elevational view of the conveyor belt of FIG. 2;

FIG. 5 is a right side elevational view of the conveyor belt of FIG. 2;

FIG. 6 is a left side elevational view of the conveyor belt of FIG. 2;

FIG. 7 is a top plan view of the conveyor belt of FIG. 2;

FIG. 8 is a bottom plan view of the conveyor belt of FIG. 2;

and,

FIG. 9 is an isometric view of a bottom, rear, and left side of the conveyor belt of FIG. 2.

The dashed broken lines in the figures depict environmental structure and form no part of the claimed design. The dash-dot-dash broken lines depict boundary lines and form no part of the claimed design.

1 Claim, 5 Drawing Sheets
